CLAIM

The ornamental design for a cellular phone with a graphic user interface, as shown and described.

DESCRIPTION

FIG. 1 is a perspective view of a cellular phone with a graphic user interface showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front view of the cellular phone with a graphic user interface showing my new design in a state in which the cellular phone (shown in broken lines) is open when in use. The broken lines in the drawings are for illustrative purpose only and form no part of the claimed design.
